(57) **CLAIM**

The ornamental design for a bird feeder, as shown and described.

DESCRIPTION

FIG. 1 is a perspective view of a bird feeder showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, shown in an environment of use.

The broken lines illustrate portions of the bird feeder that form no part of the claimed design. The broken lines showing a hook in FIG. 8 are for the purpose of illustrating environmental structure, and form no part of the claimed design.

1 Claim, 8 Drawing Sheets
